JOSEPH L. HERZOG, OF NEW YORK, N. Y.

CIGAR-LIGHTER.

1,034,617.

Specification of Letters Patent.

Patented Aug. 6, 1912.

Application filed March 14, 1912. Serial No. 683,801.

To all whom it may concern:

Be it known that I, JOSEPH L. HERZOG, a citizen of the United States, and a resident of New York, borough of Manhattan, in 5 the county of New York and State of New York, have made and invented certain new and useful Improvements in Cigar-Lighters, of which the following is a specification.

My invention relates to cigar lighters designed to be carried in the pocket, and of the type wherein a wick or a similar absorbent material kept saturated by an easily ignitable fluid is lighted by a series of sparks generated by movement of a spark-producing substance, such for example as an alloy containing a metal or metals of the cerium group with a sub-oxid or nitrid of said metals, or an alloy of cerium and iron, in contact with an abrasive member, the cigar 15 or cigarette being lighted from the flame thus produced at the wick, the object thereof being to provide a lighter in which the flame will be protected so that it will not be blown out by comparatively slight air currents as is commonly the case in lighters of 20 the type above referred to; to provide a lighter which may be readily and cheaply manufactured, and simple in construction so that it will not be likely to get out of order 25 or fail to operate, and one that is compact and of such shape that it may be readily carried in the vest pocket, and to provide such other improvements in and relating to lighters of the type above referred to as are 30 hereinafter described and claimed, and illustrated in the accompanying drawing wherein the preferred embodiment of my invention is illustrated.

In the drawing: Figure 1 is a view showing my improved cigar lighter in its closed adjustment in side elevation, with portions of the external casing thereof broken away to show the interior construction; Fig. 2 is a view showing a section of the principal 45 parts thereof taken upon a vertical central plane, and in its open adjustment; Fig. 3 is a view showing the upper end of my device in side elevation as seen from a position to the right of Fig. 2, the same being closed; Fig. 4 is a similar view showing the parts in the open position assumed when the lighter is to be used; Fig. 5 is a view showing a section taken upon a transverse plane indicated by the line 5-5, Fig. 2; Fig. 6 is a 50 view taken upon a central vertical plane and showing the upper end of my device en-

larged; Fig. 7 is a view showing a section taken upon a transverse plane indicated by the line 7-7, Fig. 6; Fig. 8 is a view showing a somewhat enlarged section taken upon a transverse plane indicated by the line 8-8, Fig. 1; Fig. 9 is a view principally in section of the lower end of the lighter illustrating the inverted position assumed by the parts when the supply of burning fluid is to be replenished; and, Fig. 10 is a view showing a reciprocating member forming a part of my device isolated, and in side elevation.

My improved cigar lighter comprises an external casing 10 within which is located a reciprocating member which carries and supports various of the elements upon which the operation of my device depends, said reciprocating member being shown separately in Fig. 10 and designated as a 75 whole by the reference character 11. A liquid reservoir 12 is formed in the lower portion of said reciprocating member, and within which a wick 13 is located, extending through the upper wall of the reservoir 80 at 14 so that it may be lighted, although it will be obvious that other forms of absorbent member kept moist by the fluid within the reservoir and extending without the same may be used; it being understood that 85 the fluid contained in the reservoir and which supplies the wick will be one which may be easily ignited to produce a flame at the outer end thereof, among which fluids alcohol, benzin, gasoline, etc., may be mentioned.

The lower end of the external casing 10 is provided with an opening 15, and the lower end of the reservoir 12 with a filling opening 16, normally closed by a screw plug 95 17, so that when the reciprocating member 11 is depressed within the casing the filling opening will be brought into a position adjacent the opening 15 whereupon the plug 17 may be readily removed, as illustrated in 100 Fig. 9, the lighter being held with its lower end upward at such times as will be understood.

A spring 18 is located within the lower end of the external casing 10 and acts upon 105 the lower end of the reciprocating member aforesaid, the tendency of said spring being to force said member upward within the casing.

The upper end of the reciprocating member 11 extends beyond the upper end of the external casing 10 and carries a cap-piece 110

19 which may be engaged by the finger to depress the reciprocating member, which cap-piece includes a projecting portion 20 which slides in a recess or cut-out portion 21 formed in the wall of the external casing, 5 as best shown in Figs. 3 and 4, so that when the reciprocating member is depressed, the projecting portion aforesaid forms a continuation of the external surface of the casing 11 and provides a lighter having a smooth outer surface.

10 From the foregoing it will be understood that by such a construction and arrangement of the several parts the projecting portion 20 extending flush or below the outer surface of the external casing avoids all danger of the lighter being accidentally opened while in the pocket of the wearer, which is always liable to occur when such 15 projecting portion extends out beyond the outer surface of the casing, as is commonly the case in the ordinary form of lighters.

20 The cut-out portion 21 above referred to provides an opening giving access to the flame, the upper end of the wick and the flame being adjacent the said opening when the reciprocating member is in its upper position and ready for use as hereinafter explained, and as illustrated in Fig. 4.

25 The cap-piece 19 is shown as provided with a spring-pressed latch member 22 the free lower end of which enters a hole 23 formed in the casing 10 when the reciprocating member 11 is in its lowermost position, as shown in Fig. 6, at which time the opening 21 is closed and the lighter is in condition to be carried in the pocket. When, however, the free end of the latch member is forced out of the hole 23, which 30 may be done by the thumb-nail as will be understood from Fig. 3, the spring 18 will force the reciprocating member 11 upward, the wick 13 will be lighted as next explained, and the opening 21 uncovered so that a cigar may be lighted from the flame. The latch member 22 engages a suitable stop at the end of the upward movement of the reciprocating member so as to limit the upward movement thereof, which stop is shown 35 as in the form of a ledge or band 24 at the upper end of the casing and serving also as a strengthening means therefor, an opening 25 being provided in the upper end of the casing 10 so that the latch 22 may be pressed inward to clear the stop or band when the reciprocating member 11 is to be withdrawn entirely from the casing, or farther therefrom than its normal uppermost position.

40 The mechanism whereby the upper end of the absorbent member, or wick 13, is ignited and a flame thus established, as the reciprocating member 11 moves upward, is as follows: An abrasive member 26 similar 45 in form to a file is located within the ex-

ternal casing 10 and suitably secured in place, the reciprocating member 11 and cap-piece 19 being provided with longitudinally extending alined grooves 27, 28 to accommodate said abrasive member and permit longitudinal movement of the reciprocating member relatively thereto. The reciprocating member is provided with a barrel 29 having a passage 30 extending at right angles to the abrasive member 26, and within which is located a spark producing element 31, which when moved along and in contact with said abrasive member will produce a series of sparks directed toward the upper end of the wick 13, and ignite the same. The spark producing element 31 is forced toward and kept in contact with the abrasive member 26 by means of a spring 32 shown as secured to and carried by the reciprocating member 11 by means of a screw 33, the lower end of said spring operating in a slot 34 formed in the upper side of the barrel 29.

45 I prefer to provide my improved igniting device with means for covering or inclosing the upper end of the wick 13 when the device is not in use, as evaporation of the volatile ignitable liquid employed is thereby prevented and the wick kept in such condition that it will more surely be ignited by the sparks produced as aforesaid when the device is to be used. The drawing illustrates one form of such a means, the same comprising a hood 35 designed to fit over the upper end of the wick when the reciprocating member is depressed, said hood being carried at one end of a lever 36 pivoted to the reciprocating member 11 at 37, and the other or free end 38 of which lever moves adjacent the inner surface of the casing 10 and engages a stationary stop or lug 39 thereon as said reciprocating member approaches the end of its downward movement, whereupon the lever will be swung upon its pivot and the hood moved into position to cover the end of the wick. As the lever is swung upon its pivot, the free end 38 thereof enters a hole or recess 40 formed in the casing 10, and, when the reciprocating member 11 is released by forcing the latch member 22 from the hole 23, the free end 38 of the lever 36 contacts with the wall of the hole or recess 40 and the hood 35 moved upward and away from the upper end of the wick, so that the sparks produced may reach and ignite the same. The lever 36 is so designed and proportioned, as will be understood from Fig. 2, that it may swing upon its pivot at 37 only when the free end 38 thereof may enter the hole 40, from which it follows that the hood is held away from the end of the wick except when the reciprocating member is at the lower end of its movement, it being necessary that the hood be removed from the end of the wick simultaneously

with the beginning of the upward movement of said member. A longitudinally extending groove 41 is provided in the reciprocating member 11 within which the projecting lug 39 lies, and whereby reciprocating movement of said member is permitted.

When it is desired to supply a new spark producing element 31 the spring-pressed latch member 22 is pressed inward so as to 10 clear the stop or band which limits the normal upward movement of the reciprocating member 11, thus permitting said member to move farther and into the position shown in dotted lines in Fig. 2. This movement 15 exposes the left-hand end of the passage 30 in the barrel 29 and permits a new spark producing element to be placed therein.

From the foregoing it will be understood that my improved lighter is of a shape, and 20 can be made of a size peculiarly well adapted for carrying the same in the vest pocket, as it is tubular in form and about the length of the ordinary pocket knife. Again, the inner tubular reciprocating member is of 25 such size that it may contain a wick or absorbent member of greater length than is usual in the ordinary form or type of lighter, thus enabling it to receive and contain a larger volume of the lighting fluid, and by 30 reason of the length of the reciprocating member and the consequent distance it travels in opening, will insure a much greater number of sparks, and the certainty of its lighting the wick, than has heretofore been 35 possible; and, finally, by reason of the fact that the abrasive material is stationary and straight in its length, the production of the sparks by the contacting of the said spark producing alloy therewith is rendered far 40 more certain than where one of the parts rotates upon an axis, as is usually the case.

While I have shown my invention as embodied in a mechanism of particular and definite form and construction, it will be understood that the same may be embodied in other forms, and that my invention includes such variations and modifications of the particular embodiment thereof illustrated and described as will be obvious to those skilled 50 in the art to which my invention relates.

What I claim is:—

1. An article of the character described comprising an external casing having an opening in its lower end, a reciprocating member containing a reservoir and located within said outer casing, said reservoir having a filling opening at its lower end, means for holding said internal reciprocating member within said outer casing when in its open and closed adjustment, and means for producing a series of sparks during the outward movement of said inner casing.

2. An article of the character described comprising an external casing, a reciprocat-

ing member containing a reservoir and located within said external casing, said reciprocating member being shorter than said external casing so that it may enter thereto, means for holding said reciprocating member within said outer casing when the same is moved thereinto, and means for producing a series of sparks during the outward movement of said reciprocating member.

3. A device of the character described comprising an outer tubular casing, a tubular reciprocating member contained within said outer casing and provided with a reservoir containing a protruding wick, means for locking the reciprocating member within said outer casing, an abrasive member carried by said outer casing, a spark producing element carried by said reciprocating member, whereby a series of sparks is produced to ignite said wick during the movement of said reciprocating member, and means for moving said reciprocating member outward upon disengagement of said locking means.

4. In a device of the class described, an external casing; an abrasive member within said casing; a reciprocating member within said casing; a reservoir carried by said reciprocating member and having a wick extending without the same; a spark producing element carried by said reciprocating member and adapted to contact with said abrasive member; means for moving said reciprocating member within said casing; and means for locking said reciprocating member in a depressed position within said external casing.

5. In a device of the class described, an external casing; an abrasive member within said casing; a reciprocating member within said casing the upper end of which projects therefrom; a reservoir carried by said reciprocating member and having a wick extending without the same; a spark producing element carried by said reciprocating member and adapted to contact with said abrasive member; and a spring within said casing and in operative engagement with said reciprocating member.

6. In a device of the class described, an external casing; an abrasive member within said casing; a reciprocating member within said casing the upper end of which projects therefrom; locking mechanism adapted to hold said reciprocating member in a depressed position within said casing; a reservoir carried by said reciprocating member and having a wick extending without the same; a spark producing element carried by said reciprocating member and adapted to contact with said abrasive member; and a spring within said casing and acting to force said reciprocating member outward.

7. In a device of the class described, an

4

external casing; an abrasive member within said casing; a reciprocating member within said casing the upper end of which projects therefrom; a spring-pressed latch carried by said reciprocating member and adapted to engage said casing to hold said reciprocating member in a depressed position therein; means whereby said latch may be disengaged from said casing; a reservoir carried by said reciprocating member and having a wick extending without the same; a spark producing element carried by said reciprocating member and adapted to contact with said abrasive member; and a spring within said casing and in operative engagement with said reciprocating member.

8. In a device of the class described, an external casing having an opening in its lower end; an abrasive member within said casing; a reciprocating member within said casing; a reservoir carried by said reciprocating member and containing a wick, said reservoir having a filling opening at its lower end; a spark producing element carried by said reciprocating member and adapted to contact with said abrasive member; and means for moving said reciprocating member within said casing.

30 9. In a device of the class described, an

external casing; an abrasive member within said casing; a reciprocating member within said casing the upper end of which projects therefrom; locking mechanism adapted to hold said reciprocating member in a depressed position within said casing; a reservoir carried by said reciprocating member and containing a wick; a spark producing element carried by said reciprocating member and adapted to contact with said abrasive member; a spring within said casing and acting to force said reciprocating member upward; a lever pivotally connected with said reciprocating member one end of which moves adjacent the inner surface of said casing; a lug upon the inner surface of said casing and with which the end aforesaid of said lever engages as said reciprocating member approaches the end of its downward movement; and a hood carried by the other end of said lever and adapted to cover the end of said wick.

Signed at New York, borough of Manhattan, in the county of New York, and State of New York, this 12th day of March 55
A. D. 1912.
